(57) **CLAIM**

The ornamental design for an insulated bag, as shown and described.

DESCRIPTION

FIG. 1 is a top front perspective view of an insulated bag, showing my new design;

FIG. 2 is a top rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan elevation view thereof;

FIG. 9 is a perspective view thereof, shown in an environmental use; and,

FIG. 10 is a cross-sectional view thereof, taken along line 10-10 in FIG. 9; shown in enlarged scale.

The evenly spaced broken lines shown in shown in FIGS. 9 and 10 depict environmental subject matter only and form no part of the claimed design.

1 Claim, 5 Drawing Sheets
